UNITED STATES PATENT OFFICE

CHARLES B. SHEPHERD, OF NEW YORK, N. Y., ASSIGNOR TO THE P & M COMPANY, OF CHICAGO, ILLINOIS, A CORPORATION OF ILLINOIS

RAIL ANCHOR

Application filed May 17, 1928. Serial No. 278,364.

This invention relates to those devices designed to prevent the longitudinal creeping of rails and known as rail anchors.

This invention has for an object a rail anchor which can be manufactured very cheaply and is capable of being applied to a rail with either side next to the cross-tie without applying as rights and lefts or having to apply one anchor from the middle of the track on one rail and the opposite anchor from the outside of the track on the other rail.

Another object of this invention is a rail anchor having a substantially triangular-shaped spring loop adapted when applied to exert resilient pressure transversely of the rail and also provide a relatively yieldable portion which facilitates the application of the anchor to a rail.

Other objects will appear from the following description, appended claims and the accompanying drawings in which:

Figure 1 illustrates the rail anchor constituting this invention applied in position on the base portion of a railroad rail, the said rail base being shown in section.

Figure 2 illustrates one of the positions assumed by the anchor in the course of its application to a rail base, the rail base being shown in section.

Figure 3 is a side elevation of the anchor illustrating the distortion of the arm and loop portions of the anchor (in dotted lines) after the anchor has been applied to its operative position on a rail.

Referring to the drawings wherein an embodiment of my invention is illustrated, there is disclosed a rail anchor which is capable of being formed by bending hot a single piece of bar steel, preferably rectangular in cross-section. The reference numeral 1 designates a body member or arm adapted to extend transversely beneath the bottom surface of the rail base flange. Disposed on opposite ends of the body member are the rail flange-engaging means 2 and a substantially triangular-shaped loop or spring member 3 on which there is disposed a rail flange-engaging means 4. The rail flange-engaging means 2 may be of any desired shape or form.

In the embodiment illustrated, it is shown as an upstanding lip, its inner surface 5 being adapted to engage the vertical edge of a rail base flange.

The rail flange-engaging means 4 comprises a jaw 6 adapted to engage the upper surface of a rail base flange and exert a downward pressure thereon. The shape of this jaw may be of any form or contour. Preferably, I make it with an angle corresponding substantially to the inclination of the upper surface of the rail base flange which it is intended to engage and grip. Disposed beneath this jaw 6 is a jaw 7 adapted to engage the bottom surface of a rail base flange at points substantially opposite to the points engaged on the upper surface of said flange by the jaw 6. These two jaws are spaced so that a rail base flange may be received therebetween without the application of great applying force until it reaches an imaginary vertical plane 8, through the points 9 and 10 (Figs. 2 and 3). Further applying movement of the rail anchor, for example, movement of the device from the position shown in Fig. 2 to the position shown in Fig. 1, is effected by a driving force and causes the jaws 6 and 7 to tightly wedge and securely grip the top and bottom surfaces of the base flange embraced. A curved member 11 joins or connects the upper and lower jaws and is spaced from and does not engage the vertical edge of the rail base flange gripped by the jaw. Normally, the distance between rail engaging surfaces of the jaws 6 and 7 and flange-engaging surface 5 of the lip 2 when the anchor is free of the rail, is such that it is necessary to increase the effective length of the arm to permit engagement of the lip 2 over the edge of the base flange. This increase in the effective length of the arm 1 is effected by the tendency which the upward pressure of the arm 1 against the bottom of the rail has to open or spread the arms 12 and 13 of the spring loops as shown in dotted lines in Fig. 3.

As previously pointed out, the body member 1 and the jaw 7 are joined together by means of the substantially triangular loop 3. This latter portion of the anchor comprises the legs 12 and 13 and the base member 14. The rail flange-engaging means 2 may be of any desired shape or form.

The horizontal base member 14, is preferably straight as illustrated in the drawings so as to provide a relatively wide tie abutting portion, but this particular portion of the loop 5 may be made of any other suitable configuration. The legs 12 and 13 are preferably curved, as illustrated in the drawings, and normally in contact, or substantially so, at their upper extremities when the anchor is 10 free of the rail. Due to the arrangement and design of the parts, legs 12 and 13 contact at their curved portions during the initial position of the anchor on the rail base flange (Fig. 2) but are spread apart slightly by the downward flexing of the arm 1 during the further applying movement. When applied to the 15 rail the triangular spring member also functions as a tie-abutting means.

To increase the holding grip and pressures 20 exerted by the anchor when in position on a rail base flange, various parts of the anchor are disposed to exert different pressures. The portion 15 of the arm or body member 1 adjacent the lip 2 is normally disposed in a plane 25 higher than the plane occupied by the body member 1 but is flexed downwardly as above mentioned during its final applying movement. The lower jaw 7 is also formed to lie in a plane higher than the inner portion of 30 the body member 1, which may be, if desired, the same plane as occupied by the portion 15.

In application, the jaw member 4 is placed 35 by hand on the rail in the position shown in Fig. 2. It is then driven on a rail base flange until the jaw cannot travel any further. In this position the jaw portion of the anchor assumes the position illustrated in Figure 1 with the lip 2 in a position below the rail base somewhat closer to the edge of the rail 40 than that shown in Fig. 2. Pressure is then applied to the anchor by any suitable means, such as by striking the triangular spring member 3 on the outer surface of the curve 16 with a sledge or spike maul. Continued 45 application of pressure causes the lip 2 of the arm member 1 to clear the edge of the rail base flange and snap into position.

After application, the forces and pressure 50 becoming distributed throughout the anchor, the triangular spring member in tending to resume its normal position exerts a spring force transversely of the rail. When applied in position, the anchor will exert a powerful transverse pressure at 5 and an upward pressure at 7 and 15. Downward pressure will 55 be exerted by the jaw 6.

The anchor above described is economical 60 and cheap to manufacture. In position on a rail base flange it functions very efficiently. 65 The manner or mode of application is simple and easy. Due to its design, it is capable of being applied to a rail with either side next to the cross-tie without applying as rights and lefts. With my anchor it is not necessary 70 to apply one anchor from the middle of the

track on one rail and the opposite anchor from the outside of the track on the other rail. My anchor may be applied from either or both 75 positions.

Since it is obvious that various modifications and changes such as shape, size, disposition, etc. of the legs may be made without departing from the nature of the invention, I do not intend to limit myself to the exact 75 and specific details above described, except as defined and set forth in the following 80 claims.

I claim:

1. A rail anchor comprising oppositely disposed rail base flange-engaging means and a spring loop disposed between said rail base flange-engaging means, said loop being provided with a relatively straight base and converging legs which give the loop a triangular 85 configuration.

2. A rail anchor comprising oppositely disposed rail base flange-engaging means and a substantially triangular-shaped spring member disposed between said rail base flange-engaging means, said spring member having its legs spaced apart when applied to a rail and adapted to contact with each other when 90 free of the rail.

3. A rail anchor comprising oppositely disposed rail base flange-engaging means and a substantially triangular-shaped spring member disposed between said rail base flange-engaging means to provide resilience transversely of the rail and a relatively wide tie abutment, said spring member having outwardly curved legs which converge toward 95 their upper ends.

4. A rail anchor comprising oppositely disposed rail base flange-engaging means and a substantially triangular-shaped spring member disposed between said rail base flange-engaging means, said spring member having curved legs, the upper ends of said legs being in contact when the anchor is free of the rail but are spread slightly by the distortion of 100 the anchor during its applying movement.

5. A rail anchor comprising oppositely disposed rail base flange-engaging means and a substantially triangular-shaped spring member disposed between said rail base flange-engaging means, said spring member having curved legs, the upper ends of said legs being normally spaced apart when in applied position on the rail and adapted to contact with 115 each other when free of the rail.

6. A rail anchor comprising oppositely disposed rail base flange-engaging means and a substantially triangular-shaped spring member disposed between said rail base flange-engaging means, said sprng member having curved legs, the upper ends of said legs being normally spaced apart when in applied position on a rail and adapted to contact with each other at their curved portions during the in- 125

itial application of said anchor to a rail base flange.

7. A rail anchor comprising oppositely disposed rail base flange-engaging means and a substantially triangular-shaped spring member disposed between said rail base flange-engaging means, said spring member having curved legs, the upper ends of said legs being normally spaced apart when the device is in its applied position and adapted to contact with each other at their curved portions during the initial applied position of said anchor to a rail base flange and assume their normally spaced apart position after application.
- 15 8. A rail anchor comprising a body member, rail flange-engaging means disposed on one end thereof, a substantially triangular-shaped spring member having a straight base and connected at one end thereof to the other end of said body member, said spring member having legs normally spaced apart when in applied position on a rail, and rail flange-engaging means disposed on said spring member.
- 25 9. A rail anchor comprising a substantially triangular-shaped spring member having curved legs, said legs being normally spaced apart when the anchor is in its applied position and adapted to contact with each other at their curved portions during the initial application of said anchor to a rail base flange, a body member disposed on one of said legs, a jaw adapted to engage a rail base flange disposed on the other leg, and a lip adapted to engage a rail base flange disposed on the other end of said body member.
- 35 10. A rail anchor comprising a substantially triangular-shaped spring member having a straight base and converging legs, said legs being normally forced apart, by the applying force, from a position normally in contact with each other at their curved portions during the initial application of said anchor to a rail base flange and to assume said spaced position after application, a body member disposed on one of said legs, a jaw adapted to engage a rail base flange disposed on the other leg, and a lip adapted to engage a rail base flange disposed on the other end of said body member.

In testimony whereof, I have affixed my signature to this specification.

CHARLES B. SHEPHERD.
